M. KRUPA.

LOCKING DEVICE FOR COAL CUTTING TRUCKS.

APPLICATION FILED DEC. 4, 1917.

1,311,901.

Patented Aug. 5, 1919.

Inventor

MICHAL KRUPA

By Attorney. Oscar Geier

UNITED STATES PATENT OFFICE.

MICHAL KRUPA, OF JEROME, PENNSYLVANIA, ASSIGNOR OF ONE-FOURTH TO JOSEPH DZINGEL, OF JEROME, PENNSYLVANIA.

LOCKING DEVICE FOR COAL-CUTTING TRUCKS.

1,311,901.

Specification of Letters Patent.

Patented Aug. 5, 1919.

Application filed December 4, 1917. Serial No. 205,320.

To all whom it may concern:

Be it known that I, MICHAL KRUPA, a subject of the Emperor of Austria, resident of Jerome, county of Somerset, and State of Pennsylvania, have invented certain new and useful Improvements in Locking Devices for Coal-Cutting Trucks, of which the following is a specification.

This invention relates to improvements in 10 coal cutters and more particularly to novel means for holding the cutting mechanism in fixed position. My invention is designed for use in conjunction with types of cutting machines for extracting coal from mines which 15 are mounted upon trucks, and the means provided in the present improvement for holding the machine in one position at a time consists of an adjustable device mounted upon the platform of the truck and 20 adapted to engage with the top of the mine, as will readily be appreciated.

These and other like objects are attained by the novel construction and combination of parts hereinafter described and shown in 25 the accompanying drawings, forming a material part of this specification, and in which

Figure 1 is a vertical sectional view.

Fig. 2 is an enlarged vertical sectional view taken through the machine securing 30 means, and

Fig. 3 is a plan and sectional view, the section being taken on line 6—6 of Fig. 2.

In the drawings, the numeral 10 indicates the rails of a track-way disposed within a 35 mine, upon which is mounted a truck 11, upon wheels 12, suited to the track and carried by the track and carried by the truck 11, is a platform 15, carrying the picks of a coal cutter mechanism illustrated but forming 40 no part of my present invention.

In order to hold the apparatus in position while the picks are operating, a footing 42 is secured on top of the platform 15, the same supporting a threaded stem 43, extending 45 vertically upward and slidably engaging within an opening 44, formed in the cylindrical contacting plug 45, the head of which may engage with the top of the drift or mine when it is desired to hold the truck 50 rigid.

In order to adjust the height of the plug 45 relative to the screw 43, a disk 48 having operating handles 49, is formed with an opening 50 through which the screw 48 passes and a lateral recess 51, extended 55 therefrom in which is engaged a block 53, the inner end of the block having teeth engageable with the screw thread 43, so that the disk operates in the manner of a nut. Means for operating the block is provided 60 by the screw stem 54, formed with the head 55, which may be operated in a manner similar to the extending handle 49.

Obviously when the block 53 is moved outwardly, the plug can be freely moved up or 65 down upon the screw 43 and when the plug 53 is engaged with the screw, the disk 48 can be used as a nut, locking the machine in its adjusted position.

Having thus described my invention what 70 I claim as new and desire to secure by Letters Patent, is—

In combination, a support, a vertically-extending threaded stem secured upon said support, a sleeve longitudinally slidable 75 upon said threaded stem, a disk formed with a central enlarged opening in which said stem is adapted to project loosely, said opening being formed with a lateral enlargement to provide a radial recess, a block slidable in 80 said recess enlargement and formed with an arcuate surface having teeth, a plurality of handle bars mounted radially of said disk, and carrying balls upon their free ends, a screw-bolt threaded into said disk and advanceable 85 therein, said screw bolt having a head rotatably secured in said block so as to support said block within said recess, and a ball head upon said screw-bolt, said screw-bolt adapted to move said head within said 90 recess enlargement and so that its teeth may mesh with the threads of said stem whereupon said disk may screw upon said stem, said disk supporting said sleeve.

In testimony whereof I have affixed my 95 signature.

MICHAL KRUPA.
